Primary Examiner — Karen E Kearney*Assistant Examiner* — Katherine A Holbrow(74) Attorney, Agent, or Firm — Shumaker, Loop & Kendrick, LLP; Jeffrey B. Fabian(57) CLAIM

The ornamental design for a display screen with graphical user interface for social media website, as shown and described.

DESCRIPTION

The FIGURE is a front view of a display screen with graphical user interface for social media website showing our new design.

The broken lines showing the display screen and portions of the graphical user interface are included for the purpose of illustrating portions of the article and form no part of the claimed design.
